PRESSURE RESPONSIVE RATIO RELAY

Robert R. Donaldson, Pittsburgh, Pa., assignor
to John M. Hopwood, Mount Lebanon, Pa.

Application June 10, 1940, Serial No. 339,692

5 Claims. (Cl. 137—153)

This invention relates to relay devices and more particularly to ratio relays adapted to respond to an actuating force or impulse and to send out another force or impulse that bears a definite predetermined relationship to the actuating force.

The device embodying the invention herein illustrated and described is of the type shown in United States Patent Number 2,016,824 granted to G. W. Smith on October 8, 1935, and adapted to perform the same functions and to be used for the same purposes as the ratio relay of said patent.

An object of this invention is to provide a ratio relay that shall represent a distinct improvement over the relay device of Patent 2,016,824 in the construction and arrangement of parts and particularly in the form and construction of the force or impulse-responsive element and the sending valve mechanism.

Another object of the invention is to provide an improved nonsticking valve mechanism that shall be more positive and sensitive in its performance.

A further object of the invention is to provide a means for eliminating vibration of the valve assembly and force-responsive actuating element.

The above and other objects of the invention will be apparent to those skilled in this art from the following description taken in conjunction with the accompanying drawings in which:

Figure 1 is a view in section taken on line I—I of Fig. 2 of the ratio relay device embodying the improvements constituting the invention;

Fig. 2 is a top plan view of the device;

Fig. 3 is a bottom view of the device; and

Figs. 4, 5, and 6 are views in section taken on line IV—IV, V—V, and VI—VI of Fig. 1, showing details of construction in their assembled relationship.

Throughout the drawings and the specification like reference characters indicate like parts.

The operation and general arrangement of the device shown in the drawings for the purpose of illustrating the principles of my improved ratio relay or ratioing device, will first be described with reference to Fig. 1, followed by a detailed description of the construction, arrangement, and assembly of the various parts or elements of the device.

The relay device comprises in general a body 1 having at its opposite ends chambers 2 and 3 formed in the under side thereof. These chambers are closed by means of diaphragms 4 and 5 which, as will be described hereinafter, are

clamped to the under side of the body in pressure-tight relationship so that these chambers are pressure tight.

Chamber 2 may be designated a receiving chamber, that is it responds to pressures introduced into it from a pipe 6; and chamber 3 may be considered as a sending chamber, that is a pressure medium from an independent supply pipe 7 is introduced into this chamber under the control of a valve 8 and is sent out from the chamber to a sending line 9 serving regulators or other devices (not shown but see Patent 2,016,824) to be actuated by and in accordance with this sending line pressure.

15 A beam 10 is supported at its opposite ends from the diaphragms 4 and 5 respectively, the ends thereof being rigidly secured to the diaphragms at their central portions. Compression springs 11 and 12 are disposed at the ends 10 of the beam and are mounted to exert upward forces on the beam, as seen in Fig. 1, in opposition to the forces produced by the pressure media chambers 2 and 3 and acting on respective diaphragms 4 and 5.

20 A fulcrum 13 is adjustably supported above beam 10 and serves as a point about which the beam may tilt or rock.

25 Springs 11 and 12 may be of such size and stiffness and the compression thereof so adjusted that they will exert an upward force at each end of the beam of any predetermined value, say ninety pounds, or sixty pounds, or any other value desired or that may be required by the range of pressures received from pipe 6 and to be sent or transmitted through pipe 9. The specific values mentioned above are merely suggestive, as the value of the forces exerted by springs 11 and 12 may be expressed in general terms A (spring 11) and B (spring 12).

30 The forces exerted by diaphragms 4 and 5 as the result of the pressure existing in chambers 2 and 3 respectively will of course be proportional to the pressure expressed in lb./sq. in. multiplied by the area of the diaphragms. For convenience, 35 the force exerted by the pressure in chamber 2 on diaphragm 4 and the force exerted on diaphragm 5 by the pressure in chamber 3, may be given the general values x and y respectively. Therefore the resultant forces R_1 and R_2 acting 40 on the ends of beam 10 may be expressed as follows: $R_1 = (A - x)$ and $R_2 = (B - y)$. So long as forces A and B are greater than forces x and y , these resultant forces R_1 and R_2 will act in the direction of the arrows employed in Fig. 1 to 45 designate them.

40

45

50

55

Since the resultant force R_1 tends to turn beam 10 clockwise, and resultant force R_2 tends to turn it counter-clockwise, beam 10 will be in balance only when the moments of these forces are equal. The turning moments are in balance when $R_1 \cdot L_1 = R_2 \cdot L_2$. But $R_1 L_1 = (A-x) L_1$ and $R_2 L_2 = (B-y) L_2$; therefore $(A-x) = L_2/L_1 (B-y) = k(B-y)$, k being the value of L_2/L_1 . When L_1 equals L_2 , $k=1$, therefore the relay beam is in balance when $(A-x) = (B-y)$.

As stated above, the value of x is determined by the pressure per unit area received by chamber 2 and the area of diaphragm 4, and the value of y is determined by the pressure per unit of area (as lb./sq. in.) sent out from chamber 3 and the area of diaphragm 5. Therefore, the value of pressure sent out and the value of y will be determined by the values of A , B , x , and the value of k . If the areas of diaphragms 4 and 5 exposed to the received and sending pressures are unity, say one sq. in., the values of x and y will be the same as the received and sending pressures.

If it be assumed that the areas of diaphragms 4 and 5 are equal to one sq. in. and that forces of springs 11 and 12 are equal, in which case forces A and B are equal, and that $k=1$, and if it be assumed that A and B are, for purposes of explanation, adjusted to ninety lb. each then the relay will operate to maintain the relation $(A-x) = (B-y)$ as shown by Table I in which values of x , $(A-x)$, R_1 , y , $(B-y)$ and R_2 are given.

Table I

Value of x	$(A-x) = R_1$	Value of y	$(B-y) = R_2$
0.....	(90-0)=90	0.....	(90-0)=90
10.....	(90-10)=80	10.....	(90-10)=80
20.....	(90-20)=70	20.....	(90-20)=70
30.....	(90-30)=60	30.....	(90-30)=60
40.....	(90-40)=50	40.....	(90-40)=50
50.....	(90-50)=40	50.....	(90-50)=40
60.....	(90-60)=30	60.....	(90-60)=30
70.....	(90-70)=20	70.....	(90-70)=20
80.....	(90-80)=10	80.....	(90-80)=10
90.....	(90-90)=0	90.....	(90-90)=0

From the above it will be seen that as the received pressures or forces x increase from zero to ninety the sending pressure for forces y increase from zero to ninety in the same increments and are equal to the values of x at all points, and that the resultant forces R_1 and R_2 are equal and decrease by the same amounts from ninety lb. to zero. Thus the resultant forces R_1 and R_2 will decrease from values ranging from the maximum value of forces A and B depending on the spring tension for which springs 11 and 12 are set, down to zero provided the forces x and y respectively are increased from zero to a value equal to the forces of the springs, namely forces A and B . Thus it follows that a change in the value of R_1 unbalances the beam so that the valve 8 will be operated to establish a pressure in chamber 3 that will restore R_2 to a value that balances the beam against the resultant force R_1 . Likewise if there is a change in pressure in chamber 3 without a corresponding change in chamber 2, diaphragm 5 will act to so operate valve 8 that the pressure in chamber 3 will be maintained constant at the value required by the pressure existing in chamber 2 and acting on diaphragm 4.

The above-described operation of the relay is the same when the value of x is decreased from a higher to a lower value, because valve 8 will be operated to lower the pressure in chamber 4 until the value of y equals the value of x .

If the same values of A and B are assumed as in the above table of values, but the value of k is changed by changing the ratio of L_2/L_1 , the relay will operate to maintain a definite relation between the values of x and y and the equation $(A-x) = k(B-y)$ will be satisfied. The values given in Table II below are obtained where k has been given a value of $\frac{1}{2}$ for convenience in dividing the expression $(B-y)$.

10

Table II

Value of x	$(A-x) = R_1$	Value of y	$k(B-y) = R_2$
45.....	(90-45)=45	0.....	(90-0)/2=45
50.....	(90-50)=40	10.....	(90-10)/2=40
60.....	(90-60)=30	20.....	(90-30)/2=30
70.....	(90-70)=20	30.....	(90-50)/2=20
80.....	(90-80)=10	40.....	(90-70)/2=10
90.....	(90-90)=0	50.....	(90-90)/2=0

By selecting a value of $k=L_2/L_1=\frac{1}{2}$ the received pressures will vary from forty-five to ninety and the sending pressures will vary from zero to ninety but the values of R_1 and R_2 are always equal and vary from forty-five to zero, thereby satisfying the equation $(A-x) = k(B-y)$.

If k or $L_2/L_1=2$ the following Table III of values show what the relation of the received pressures to the sending pressures will be.

30

Table III

Value of x	$(A-x) = R_1$	Value of y	$k(B-y) = R_2$
0.....	(90-0)=90	45.....	2(90-45)=90
10.....	(90-10)=80	50.....	2(90-50)=80
20.....	(90-20)=70	55.....	2(90-55)=70
30.....	(90-30)=60	60.....	2(90-60)=60
40.....	(90-40)=50	65.....	2(90-65)=50
50.....	(90-50)=40	70.....	2(90-70)=40
60.....	(90-60)=30	75.....	2(90-75)=30
70.....	(90-70)=20	80.....	2(90-80)=20
80.....	(90-80)=10	85.....	2(90-85)=10
90.....	(90-90)=0	90.....	2(90-90)=0

The above table of values show the relation of pressures received to pressures sent where the value of k is equal to one, is less than one, and greater than one.

The relation of the pressures received, that is pressures x , to the pressures sent, that is pressures y , may be varied from the equal and corresponding values shown in Table I where k is equal to one, by adjusting either spring 11 or spring 12 to a higher degree of tension than the other. Thus if spring 12 is adjusted to provide a value of B equal to say one hundred ten lb., the values of x , $(A-x)$, R_1 , y , $(B-y)$, and R_2 will be as shown in Table IV below.

55

Table IV

Value of x	$(A-x) = R_1$	Value of y	$(B-y) = R_2$
0.....	(90-0)=90	20.....	(110-20)=90
10.....	(90-10)=80	30.....	(110-30)=80
20.....	(90-20)=70	40.....	(110-40)=70
30.....	(90-30)=60	50.....	(110-50)=60
40.....	(90-40)=50	60.....	(110-60)=50
60.....	(90-60)=30	80.....	(110-80)=30
80.....	(90-80)=10	100.....	(110-100)=10
90.....	(90-90)=0	110.....	(110-110)=0

From the above values it is seen that when x equals zero y equals twenty, that R_1 and R_2 both equal ninety and that the values of x range from zero to ninety and the values of y range from twenty to one hundred ten. For all values, however, R_1 and R_2 are equal and vary from ninety down to zero.

If A is made equal to one hundred ten, for example, and B is made equal to ninety, the values of x will range from twenty to one hundred ten

and the corresponding values of y will range from zero to ninety.

If A is made equal to ninety and B equal to one hundred ten and k or L_2/L_1 is made equal to $\frac{1}{2}$ the values of x will range from thirty-five to ninety, the values of y will range from zero to one hundred ten and the values of R_1 and R_2 will be equal but range from fifty-five to zero.

If the same values of A and B are assumed as in the preceding tables but the value of k is changed by changing the ratio of L_2/L_1 , the relay will operate to maintain a definite relation between values x and y and the equation $(A-x)=k(B-y)$ will be satisfied as shown by Table V. In connection with Table V, k is given the value $\frac{1}{2}$ for convenience of computation.

Table V

Value of x	$(A-x)=R_1$	Value of y	$k(B-y)=R_2$
45	(90-45)=45	0	(90-0)/2=45
50	(90-50)=40	10	(90-10)/2=40
60	(90-60)=30	20	(90-30)/2=30
70	(90-70)=20	30	(90-50)/2=20
80	(90-80)=10	40	(90-70)/2=10
90	(90-90)=0	50	(90-90)/2=0

With a value of k or L_2/L_1 equal to $\frac{1}{2}$, the received pressures or forces x will vary from forty-five to ninety lb. and the sending pressures will vary from zero to ninety, that is the y forces will vary from zero to ninety, but the values R_1 and R_2 will be always equal.

If the value of k or the ratio L_2/L_1 is made equal to two, the following Table VI of values show what the relation of received and sending pressures will be:

Table VI

Value of x	$(A-x)=R_1$	Value of y	$k(B-y)=R_2$
0	(90-0)=90	45	2(90-45)=90
10	(90-10)=80	50	2(90-50)=80
20	(90-20)=70	55	2(90-55)=70
30	(90-30)=60	60	2(90-60)=60
60	(90-60)=30	75	2(90-75)=30
80	(90-80)=10	80	2(90-85)=10
90	(90-90)=0	90	2(90-90)=0

If k is made equal to two then the values of x will range from zero to ninety, but the values of y will range from sixty-five to one hundred ten, but the values of R_1 and R_2 will be equal and vary from ninety to zero.

It will be apparent that the values A and B may be adjusted as desired over a wide range and that for all values of A and B (both being greater than zero) the relative values may be changed by making k equal to one, or greater or less than one, and that the values A or B may be made equal or unequal, and that a value of k may be chosen which is equal to, greater than, or less than one.

Description of elements of the relay

Body 1 of the relay is substantially rectangular in transverse section and is preferably cast in one piece. In casing the body, cores are employed to form a hollow pressure-tight volume chamber 15 having communication with diaphragm chamber 3 through which a passageway 16, which is drilled from chamber 3 on an angle as shown. This chamber acts as a damping device to prevent vibration of valve 8 and diaphragm 5. The valve and diaphragm shown are sensitive and are subject to sustained vibrations of different frequencies and amplitudes depending on such factors as stiffness of springs 11 and 12, and diaphragm 5, the area of the inlet and exhaust

ports of valve 8, and the length and volume of sending line 9.

No single one of these factors has been found in practice to contribute more to vibration than others, but whatever the specific cause may be I have found that a volume chamber placed close to diaphragm chamber 3 will eliminate these sustained vibrations. The pressure in chamber 15, of course, varies with the sending pressures producing forces x and there is sufficient volume in chamber 15 to exert a stabilizing effect on diaphragm 5 and its co-operating elements.

In casting body 1 a core is also employed to form a substantially L-shaped hollow space 17 one leg of which is located below chamber 15 and substantially parallel to beam 10; the other leg of this hollow portion extends vertically to the top of body 1 from a point adjacent to but above diaphragm chamber 2. This hollow portion accommodates a screw 18 one end of which is journaled in the end of the body in which valve chamber 3 is formed and the other end extends through a bushing 19 in the opposite end of the body and has affixed thereto a handwheel 20 for turning the screw. Bushing 19 is threaded to receive a clamping nut 21 whereby the relay device may be supported from a panel board 22 as shown. A collar 23 is fitted on the shaft of screw 18 and placed against the inner end of bushing 19 and fastened to the shaft with a pin 24, whereby longitudinal movement of shaft 18 is prevented.

A carriage 25 has threaded engagement with screw 18 and supports fulcrum 13. Fulcrum 13 is preferably circular or wheel-like in form and is mounted on a pin or shaft 26 which extends transversely through the carriage. The bottom face of body 1 is provided with a window or slot 27 along which the carriage slides. As may be seen more clearly in Figs. 3 and 5, the carriage is formed with flanges 28 that extend under and across body 1 and serve to guide the carriage and to maintain roller fulcrum 13 in its proper position with respect to the upper face of beam 10.

In order that the ratio of L_2/L_1 or the value of k may be made visible on a gauge or indicating device, a chain 29 having one end hooked to the carriage, (as shown in Figs. 1, 2 and 3) its middle portion running under a pulley 30 secured to the receiving end of the relay and having its other end connected to the indicating device 31. Thus as carriage 25 and its fulcrum 13 are moved along screw 18 as the screw is turned, the indicator would show whether the fulcrum was at the mid-point of beam 10 or to the left or the right of this point and the position of the fulcrum can be expressed in terms of L_2/L_1 or k on the indicator.

Chamber 2 is formed by machining a recess into the bottom of body 1 to the required depth. The side of the body is drilled and tapped so that receiving pipe 6 may be fitted to the body and have communication with the interior of chamber 2.

At the other end of body 1, recess 3 is formed by machining or otherwise to the required depth. In vertical alignment with the center of chamber 3, a hole 32 is drilled and tapped that extends from the top of extension 33 of body 1 downwardly into chamber 3. Valve assembly 8 is threaded into this hole to the distance required in order to have the proper operation of the valve, and locked in place by means of a lock nut 34.

As stated previously herein, diaphragms 4 and 5 are secured rigidly to beam 10.

Diaphragm 4 comprises preferably a circular, flexible, disc-like element which is shaped as shown by the transverse section in Figs. 1 and 4. The central portion of this diaphragm is apertured to receive a bolt 35, the head of which bears on the top side of the diaphragm. The shank of the bolt extends through a bushing 36 disposed on the under side of the diaphragm but which rests on the top side of a flat end portion 37 of beam 10, and thence through the beam. The bolt is provided with a lock washer 38 positioned on the under side of the end portion 37 and a nut 39 which is drawn up tightly to insure that a pressure-tight joint is established at the point where the bolt passes through the diaphragm and also to lock the diaphragm tightly and securely to the beam.

The outer edge of diaphragm 4 is clamped tightly to body 1 around the edge of diaphragm chamber 2 by means of a clamping ring 40 which is substantially rectangular in shape at its outer periphery and which is provided with a substantially circular opening to receive the active portion of diaphragm 4, that is the portion to which the pressure in chamber 2 is exposed. Ring 40 is secured to relay body 1 by means of cap screws 42. Clamping ring or flange 40 is formed as an integral part of a substantially U-shaped yoke 43 which depends or extends downwardly therefrom and which serves as a cradle or support for spring 11. The lower end of this yoke is drilled and tapped to accommodate an adjusting screw 44 whose upper end has a journaled connection with a spring cap 45 on which the lower end of spring 11 is supported. The upper end of spring 11 encloses bolt 35 and bears against the flat end portion 37 of beam 10. By turning adjustment screw 44 upwardly through the lower end of yoke 43 any desired degree of compression may be imposed on spring 11 in order to obtain the desired or required value of force A.

Accurate operation of the relay device requires that beam 10 be rigid and stiff so that it will not deflect as the result of the forces R_1 and R_2 acting on the ends thereof. Beam 10 is therefore preferably made in one piece by casting of steel or other suitable material with T-shaped section throughout the major portion of its length. Thus the leg of the T forms a web 46 on the under side of the beam which gives stiffness and resistance to bending and the upper portion 46 provides a wide, flat face or trackway for the roller fulcrum 13.

Diaphragm 5 may be made of the same size and shape as diaphragm 4 and may be secured to the right-hand end of beam 10 by means of a bolt 47, the head 48 of which bears on the top side of the diaphragm. The shank or body of bolt 47 passes through the central portion of the diaphragm, a bushing 49 disposed on the under side of the diaphragm, and end portion 50 of the beam. The bolt is drawn up tightly to hold the diaphragm and bushing securely to the beam by means of a lock washer 51 and nut 52. Diaphragm 5 is clamped to body 1 by means of a clamping flange or ring 53 of substantially the same shape and size as flange 40. A substantially U-shaped yoke 54 of the same form and construction as yoke 43 is made as an integral part of flange 53 and serves as a support for spring 12. The upper end of spring 12 is disposed about bolt 47 and bears against the under side of beam 10 and the lower end of this spring is supported on a spring cap 55 carried on the end of an adjusting screw 56. Screw 56 is threaded upwardly through the lower end of yoke 54 whereby spring

12 may be adjusted to any degree of tension to produce the desired value of force B.

In the construction of the relay it is preferred to make diaphragms 4 and 5 of the same size, yokes 43 and 54 with their respective flanges 40 and 53 of the same size and shape so that these parts of the relay device may be interchangeable and thereby make manufacture, assembly, repairs and replacements more convenient and less expensive.

Bolt 47 forms a part of valve mechanism 8. As shown in Fig. 6 the bolt is provided with a central bore or passage 57 through the body thereof which terminates in a tapered valve port 58 in the head of the bolt. When the valve port 58 is uncovered, pressure medium escapes from chamber 3 through passage 57 to the atmosphere. The pressure medium supplied to chamber 3 flows into sending pipe 9 through a port 59 which is drilled through one side of extension 33 of the relay body into valve bore 32.

Valve assembly 8 includes a valve body 61 provided with a central bore 62 extending from one end to the other of the body. At the upper end of bore 62 a port 63 is formed having a tapered seat 64 that co-operates with a valve element 65 adapted to close or open this port. The valve element is carried at the upper end of a valve stem 66 that extends through the bore of the body into chamber 3 with its lower end nesting in the exhaust port 58. The valve stem is urged downwardly by means of a spring 67, the upper end of which rests against the lower end of valve body 61 and the lower end of which is carried on a flanged collar 68 mounted on the valve stem and supported on a shoulder 69 thereon. Lower end portion 70 of the valve stem is made larger than the upper portion so that it may be shaped and fitted to properly control exhaust port 58. Spring 67 tends to urge valve stem 66 in a direction to maintain the inlet port closed and the lower end 70 thereof in contact with the seat of exhaust port 58.

From the description of the valve assembly, excluding the part which diaphragm 5 and valve bolt 47 with the valve port 58 formed therein play in the assembly and the operation of the valve mechanism, it will be apparent that the valve is easily repaired because by disconnecting pipe 7 from the valve body, the valve body and valve stem 66 may be removed as a unit for inspection and repair. Also it will be apparent that the valve is a nonsticking type of valve and requires a very small travel in order to open fully or close fully its inlet and exhaust ports respectively. Further, the complete valve may be inspected and repaired readily because the valve seat 58 is quickly accessible by merely disconnecting yoke ring 54 from the relay body 1, the diaphragm 5 and the valve bolt 47 may be readily inspected and repaired or replaced if necessary.

To adjust the device for operation it is preferable to position fulcrum 13 at the mid-point of beam 10 so that the ratio of L_4 to L_1 is equal to one. Springs 11 and 12 are then adjusted to produce the required forces A and B, say either sixty, seventy, eighty, or ninety pounds, at the ends of the beam. When making the spring adjustments there should be no pressure in chamber 2 and valve body 61 should be turned upwardly to a position where inlet port 63 is closed and the exhaust port is uncovered. When springs 11 and 12 have been adjusted to the required tension so that values A and B are equal then valve

body 61 is turned downwardly gradually until the end of portion 70 of valve stem 66 seats on the exhaust port 58 and closes it. This point will be readily determined because if the valve body is turned too far into bore 32 valve stem 66 will be moved upwardly and the inlet port opened, allowing air or pressure medium to flow into chamber 3. A gauge could be connected to pipe 9 and by means of this gauge the correct setting of the valve body would be determined because if the gauge shows pressure in chamber 3 the valve body should be backed out until the gauge shows zero pressure. The valve body would then be locked in place with lock nut 71.

The device is now ready for operation. By introducing pressures into the receiving chamber 2 the resultant force R_1 will be made less than force A whereby force B will cause beam 10 to turn counter-clockwise and lift valve element 65 off the inlet port and allow pressure medium to flow into chamber 3 until resultant force R_2 is made equal to resultant force R_1 whereupon beam 10 will assume a level or balanced position, in which position inlet and exhaust ports 63 and 58 will be closed and there will be no further change in pressure in chamber 3. If the pressure is further increased in chamber 2 the above-described operation will be repeated and a pressure will be built up in chamber 3 until the resultant force R_2 is equal to resultant force R_1 . The opposite action takes place if the pressures received in chamber 2 are decreasing. If these pressures are decreasing then resultant force R_1 will exceed resultant force R_2 and beam 10 will tend to turn clockwise about fulcrum 13 whereby valve element 65 will be seated on and close the inlet port and the valve port 58 will be opened by its being moved away from the lower end of the valve stem portion 70, allowing pressure to escape through passage 57 to the atmosphere until resultant force R_2 is increased to a value equal to resultant force R_1 .

Having thus described the invention, what I claim as new and desire to secure by Letters Patent is:

1. A relay for ratioing received and sending pressures comprising a rigid relay body, a fulcrum, a lever positioned to rock on said fulcrum, yokes secured to said body adjacent the ends of said lever, a spring carried by each of said yokes and yieldingly engaging said lever, said springs being in compression, one acting to turn the beam in one direction about said fulcrum and the other tending to turn the beam in the opposite direction, a pressure-receiving chamber in said body adjacent one end of said lever and having an inlet to which a pressure impulse line may be connected, a pressure-sensitive member secured at its edge portion to said body and extending across said chamber and having its middle portion connected to the end of the beam adjacent thereto, the forces of pressure acting on the pressure-sensitive member of said receiving chamber opposing the force of the spring acting on the end of the beam adjacent thereto, a sending pressure chamber formed in said body adjacent the other end of said beam, a pressure-sensitive member disposed across said chamber and secured at its edges to said body, the middle portion thereof being secured to the adjacent end of the beam, said sending pressure sensitive member being with a member having an exhaust port for exhausting pressure medium from the sending chamber, a valve body supported on the relay body and extending into said receiving chamber and provided with an inlet port to which a

source of supply of sending pressure may be connected, a valve stem within said valve body and having one end disposed to seat in the exhaust port and having a portion disposed to close the inlet port, the valve stem closing both ports when the resultant forces exerted by said springs and pressure-sensitive members on said beam are in balance about the fulcrum, the valve stem closing the exhaust port and being moved with it to open the valve when the resultant force acting on the beam adjacent the receiving chamber exceeds that at the opposite end of the beam, and the valve stem moving to close the inlet port when the exhaust port moves away from the valve stem, and a volume chamber formed in said relay body and having communication with said sending chamber.

2. A relay device comprising a rigid body, a beam having a fulcrum, springs supported from said body and connected to said beam, one on each side of the fulcrum and acting in opposition to each other, a pressure-responsive device associated with one of said springs and connected to the beam so as to oppose the force exerted by such spring on the beam, and a pressure-sending means associated with the other of said springs, comprising a chamber located between said rigid body, a pressure-sensitive member extending across said chamber and connected to the beam and adapted to exert a force thereon opposing the force of the spring associated therewith, said pressure-sensitive member having an element carried thereby and provided with an exhaust valve port, a valve body associated with said chamber and provided with an inlet port to which a source of supply of sending pressure may be connected, and a valve stem within said valve body and provided with means for closing the inlet port, said stem extending into said chamber and having its inner end portion disposed to seat in the exhaust port, and means yieldingly urging the valve stem in a direction to close the inlet port, the stem being moved by the pressure-sensitive member with the exhaust port closed when moving in a direction to open the inlet port, the sensitive member moving the exhaust port away from the valve stem to open the exhaust port after closing the inlet port, and an outlet from said chamber to which a sending line may be connected.

3. A device according to claim 2 characterized by the fact that the rigid body is provided with a volume chamber, the interior of which is connected to the interior of the chamber of the pressure-sending means, said volume chamber acting to prevent vibration of the pressure-sending means.

4. A device according to claim 2 characterized by the fact that the pressure-responsive and the pressure-sending means each comprise a chamber formed in said rigid body, that each of said chambers is closed by a diaphragm the edges of which are clamped in a pressure-tight relationship to the rigid body and that the middle portions of such diaphragms are secured to the beam.

5. A device according to claim 2 characterized by the fact that the rigid body has a pressure-tight volume chamber therein which is connected by a passageway providing unobstructed communication between the sending chamber and volume chamber, which volume chamber prevents vibration of the valve stem and pressure-sensitive member associated therewith.

ROBERT R. DONALDSON.
